DECANTER

Hyman C. Berkowitz, Wendell, Idaho, assignor to Berke Brothers Distilleries Inc., Boston, Mass.,
 a corporation of Delaware

Application March 30, 1953, Serial No. 24,242

Term of patent 14 years

(Cl. D58—8)

To all whom it may concern:

Be it known that I, Hyman C. Berkowitz, a citizen of the United States, residing at Wendell, in the county of Gooding, and State of Idaho, have invented a new, original, and ornamental Design for a Decanter, of which the following is a specification, reference being had to the accompanying drawings, forming a part thereof.

In the drawings:

Fig. 1 is a top view of a decanter showing my new design; and

Fig. 2 is a side elevation taken at any desired angle.

The sides of the decanter not shown are the same as those shown.

I claim:

The ornamental design for a decanter, substantially as shown and described.

HYMAN C. BERKOWITZ.
